UNITED STATES PATENT OFFICE.

ADOLPH M. HOLSTEIN, OF SYRACUSE, NEW YORK.

DESIGN FOR A POST ORNAMENT FOR FURNITURE, CASKETS, AND FOR INTERIOR AND EXTERIOR DECORATIONS.

52,745.

Specification for Design.

Patented Dec. 10, 1918.

Application filed August 22, 1917. Serial No. 187,554. Term of patent 3½ years.

To all whom it may concern:

Be it known that I, ADOLPH M. HOLSTEIN, a citizen of the United States, residing at Syracuse, in the county of Onondaga and State of New York, have invented a new and original and ornamental Design for a Post Ornament for Furniture, Caskets, and for Interior and Exterior Decorations, of which the following is a specification, reference being had to the accompanying drawing, forming a part hereof, which is a face view of the ornamental design.

The drawing is an elevation or face view of my new and ornamental design.

Copies of this patent may be obtained for five cents each, by addressing the "Commissioner of Patents, Washington, D. C."

This design consists of a pendant representing a group of fruit, leaves, and berries gathered together at the top with a ribbon tied in a bow knot.

I claim:

The ornamental design for a post ornament for furniture, caskets, and for interior and exterior decorations, substantially as shown and described.

In testimony whereof, I have hereunto signed my name at Syracuse, in the county of Onondaga, and State of New York, this 29th day of June, 1917.

ADOLPH M. HOLSTEIN.
